UNITED STATES PATENT OFFICE

PAUL M. LATTNER, OF CEDAR RAPIDS, IOWA

HEAT-CONDUCTING MEANS FOR STEAM GENERATORS OR FLUID HEATERS

Application filed October 31, 1928. Serial No. 316,234.

This invention relates to heat exchange structures and more particularly to structures wherein heat is transmitted from a heating medium to a second medium to be heated by means of conductors cooperating with a wall or the like which separates the said media.

An important object of the invention is to provide a structure suitable for confining and placing in heat exchange relation a medium to be heated and a heating medium and to combine with said structure means for materially increasing the number of heat units transmitted from one to the other of said media and for lessening the time required to effect the transfer of said units.

A further important object of the invention is to provide a novel form of heat conducting member which is capable of use wherever it is desirable to transmit heat.

With the above and other objects in view which will more readily appear as the nature of the invention is better understood, the same consists in the novel construction, combination and arrangement of parts herein-after more fully described, illustrated and claimed.

Preferred and practical embodiments of the invention are shown in the accompanying drawings in which:

Figure 1 is a partly vertical sectional and partly elevational view of a heat exchange structure embodying this invention.

Figure 2 is a fragmentary horizontal sectional view of a portion of a shell structure and illustrates a manner of attaching heat conducting means thereto.

Figures 3 and 3^a are detail perspective views of heat conducting members.

Figure 4 is a vertical sectional view of a modified form of heat exchange structure.

Figure 5 is a detail view illustrating the manner of attaching heat conducting members employed in the structure illustrated in Figure 4.

Figure 6 is a vertical sectional view of a further modified form of heat exchange structure.

Figure 7 is a vertical sectional view of a

still further modified form of heat exchange structure, and

Figure 8 is a partly vertical sectional view and partly elevational view of another modified form of heat exchange structure.

In various figures there are several different forms of heat exchange structures illustrated but the principle of operation of each is the same in view of the fact that each structure includes the same basic combination. This combination may be briefly described in connection with all of the figures as including a member (A) which confines a heating medium in the space (B). Located in heat exchange relation with the space (B) is a further means (C) adapted for confining a medium to be heated. Suitably carried by and secured to the means (C) are a plurality of heat conducting members (D) which project into the space (B) so as to absorb heat from the medium confined therein and conduct the said heat to the medium confined within the means (C). It is to be understood of course that suitable circulating means are provided for both of the said media.

The heat exchange structure disclosed in Figure 1 consists of a conventional form of coal stove having as its means (A) an outer casing 10 which confines the products of combustion rising from the fire-box 11. The casing is provided with a flue 12 for carrying off the products of combustion. Suitably located within the casing 10 is a shell 13 which constitutes the means (C) of the combination. The shell is provided with inlet and outlet conduits 14 and 15 by means of which a liquid may be circulated through the shell. Suitably distributed over the outside of the shell 13 are a plurality of arched, heat absorbing members 16 which project into the interior of the casing 10 so as to absorb heat from the products of combustion circulating through the heat exchange chamber (B) of the combination above referred to.

Figure 2 discloses the manner of attaching the arched heat absorbing members 16 to the shell 13. In this embodiment of the invention, the arched members are cast integral with the shell 13.

In Figures 3 and 3^a there are illustrated two different forms of arched heat absorbing members. In Figure 3 the arched member 16 is constructed from solid, circular stock bent into substantially U-shape so as to provide terminals 16^a adapted to be connected, as shown in Figure 2, to a shell or the like. The arched member 16 in Figure 3^a is formed of solid, square sectioned stock and is bent into rectangular form to provide connection terminals 16^a. These two figures are intended to illustrate the possibility of making the arched heat conducting members of different sectioned material and of bending them into different shapes. It is to be understood, therefore, that the cross sectional shape of the material is unimportant and that the material may be bent into any desired shape just so terminals are provided by means of which the member may be attached to a body to be heated. The arched members, with their terminals connected to a shell or the like, will form a closed circuit and heat absorbed by the members will be conducted to the terminals and dissipated to the shell.

It is believed advisable to note at this point that wherever the term "arched" is used throughout the specification and claims, the same is intended to describe a member bent upon itself to provide relatively spaced connection terminals and as having or being without angles intermediate said terminals.

In Figure 4 the heat exchange structure is illustrated as including a shell 17 employed for confining a liquid, or the like, to be heated. This shell has suitable circulating conduits 18 and 19. Located within the shell 17 is a casing 20 adapted for confining the products of combustion rising from the gas burner 21 located below the lower open end of the said casing. Extending from the casing 20 to the outside of the shell 17 is a flue 22 by means of which the products of combustion may be discharged from the heat exchange space (B) formed in the casing. In this structure, the wall of the casing 20 separates the medium to be heated, which is located exteriorly of the casing, from the heating medium which passes through the casing. Suitably connected to the inner surface of the casing 20 and projecting into the space confined by said casing are the arched heat absorbing and conducting members 16. The arched members 16 in this embodiment of the invention are illustrated as being arranged in staggered relation with respect to each other as distinguished from the arranging of the members in rows as illustrated in Figure 1.

Figure 5 discloses the manner in which the arched members 16 are connected to the casing 20 in Figure 4. The terminals of these arched members are welded at 23 to the said casing.

In Figure 6 the means (A) includes an

outer metallic casing 24 which is provided with the insulating lining 25. Arranged within the space (B) formed in the casing 24 is metallic shell 26 having suitably arranged around its periphery the arched heat absorbing and conducting members 16. A gas burner 27 is located beneath the shell 26 and the products of combustion rising from the burner pass upwardly through the space (B) to be discharged from the latter through the flue outlet 28. Suitable circulating conduits 29 and 30 are provided for the shell 26. It will be noted that the arrangement of the arched heat absorbing and conducting members 16 in this figure includes the location of some of the same at the lower end of the shell directly above the burner 27.

The heat exchange structures illustrated in Figs. 1, 4 and 6 are especially adapted for heating liquids, such as water. It is to be understood, however, that the basic combination above referred to is not limited in its use to heating a liquid for it is equally suitable for use in the generation of steam. For this reason, Figures 7 and 8 disclose steam generators.

In Figure 7, the heating medium confining means (A) includes a casing 30 having an insulating lining 31. Arranged within the space (B) confined by the casing 30 are a plurality of shells 32. Suitably connected to the exterior of these shells and projecting into the space (B) are the arched heat conducting and absorbing members 16. This figure illustrates the arrangement of the members 16 on the respective shells so that they will overlap each other. This arrangement of the arched members will further retard the passage of the products of combustion along the shells 32 so that additional time is allowed for the absorption of the heat therefrom. Burners 33 are located beneath the shells 32 and the products of combustion from these burners may be discharged through the flue 34. The conduits 35 and 36 are arranged to connect the shells 32 in parallel.

Figure 8 discloses a casing 37 which encloses a horizontal shell 38. The medium to be heated is circulated through the shell and the products of combustion will pass from the fire-box to this steam generator structure around the shell so as to be discharged through the flue 39. Arched heat conducting members 16 are suitably arranged around the periphery of the shell 38.

It is to be understood that the forms of this invention herewith shown and described are to be taken as preferred examples of the same, and that various changes in the shape, size and arrangement of parts may be resorted to without departing from the spirit of the invention or the scope of the subjoined claims.

I claim:

1. In combination, means for confining a

medium to be heated, means for confining a heating medium in heat exchange relation with the first mentioned medium, and a plurality of arched members arranged in staggered relation with respect to each other and having the ends of their parallel leg portions connected to one of said means and projecting into the space confined by the other of said means.

5 2. A heat absorbing and conducting element for boilers and the like, comprising a conducting member adapted to be disposed in the heating zone and exterior of said boiler or the like, said member including an arched body having both ends thereof adapted to be connected to the member to be heated.

10 In testimony whereof I hereunto affix my signature.

P. M. LATTNER.
